UNITED STATES PATENT OFFICE.

DANIEL H. FRANCIS, OF GRAND JUNCTION, COLORADO.

INTERNAL-COMBUSTION ENGINE.

1,250,837.

Specification of Letters Patent. Patented Dec. 18, 1917.

Application filed December 7, 1916. Serial No. 135,650.

To all whom it may concern:

Be it known that I, DANIEL H. FRANCIS, a citizen of the United States, residing at Grand Junction, in the county of Mesa and State of Colorado, have invented a new and useful Internal-Combustion Engine, of which the following is a specification.

The present invention appertains to internal combustion engines, and aims to provide novel and improved means for controlling the intake and the exhaust, this invention being an improvement over the internal combustion engine disclosed in my co-pending application Serial No. 68,771 filed December 27, 1915.

One object of the invention is the provision of novel means for reducing the counter pressure against the controlling valve.

Another object of the invention is the provision of novel means for lubricating the valve and accompanying parts.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:—

Figure 1 is a horizontal section of the improved construction, portions being shown in plan.

Fig. 2 is a vertical section taken on the line 2—2 of Fig. 4, the valve being removed.

Fig. 3 is an elevation of the valve.

Fig. 4 is a vertical section taken on the line 4—4 of Fig. 2.

Fig. 5 is a sectional detail illustrating a modification.

A single cylinder 1 is illustrated in the drawing, but it is apparent that the invention can be used with multi-cylinder engines, as disclosed in my co-pending application.

A valve housing or casing 2 is secured to the end of the cylinder 1 to provide a head therefor, and said housing is provided with a tapered or conical bore 3, the larger end of which is open, and a cap 4 is secured in any suitable manner to the housing 2 across the larger end of the bore 3. A tapered or conical valve 5 is fitted within the bore 3

and seats thereagainst to provide a tight fit, and the housing 2 has ports 6 and 7 communicating with the interior of the cylinder, and opposite ports 8 and 9, while the valve 5 has a diametrical passage 10 adapted to communicate simultaneously with passages 6 and 9 and with passages 7 and 8. The valve 5 is rotated in any suitable manner by connecting it with the crank shaft or other rotating part of the engine, so that the passage 10 registers with the ports of the housing at the proper times during the intake and exhaust strokes of the piston. The valve 5 has a stem 14' projecting from its smaller end out of the housing 2 for rotating the valve.

As a means for reducing the counter pressure against the larger end of the valve due to the combustion of the gaseous mixture within the auxiliary explosion chamber between the larger end of the valve 5 and the cap 4, the larger end of the valve 5 is provided with a centrally located boss 11 of sufficient diameter to leave the desired area of the larger end of the valve 5 around the boss exposed to the explosion. The boss 11 is provided with packing rings 12 and is slidable and rotatable snugly within a cavity or recess 13 with which the cap 4 is provided, whereby the pressure cannot be imposed upon the face of the boss 11; thus reducing the pressure on the larger end of the valve proportional to the area of the boss 11. The housing 2 has a port or passage 14 establishing communication between the interior of the cylinder and the auxiliary explosion chamber between the valve 5 and cap 4, so that when the carbureted air is supplied into the cylinder, a small portion thereof will flow through the passage 14 into the auxiliary explosion chamber, in order that when the explosion occurs, the combustion will provide the desired pressure against the larger end of the valve 5 to force the valve against its seat during the explosion, thereby presenting a counter pressure to resist pressure which tends to force the valve from its seat.

The means for reversing the engine embodies a rotatable member 15 mounted upon the housing 2 and having the ports 16 and 17. A pivot bolt 18 is engaged downwardly centrally of the member 15 and takes into the housing 2 for pivotally mounting the member 15 on the housing, the head of the bolt 18 being seated in the port 16. The

port 17 extends to the periphery or other suitable point of the member 15, and the member 15 has a central upstanding nipple communicating with the port 16 and rotatably engaging the exhaust pipe or manifold 20 which can be stationary. A carburetor or other fuel supplying means 21 is connected to the member 15 to communicate with the inlet port 17, and the member 15 10 has a handle 22 for oscillating it through a semi-circle to reverse the member 15. As illustrated, the port 17 communicates with the port 8 and the port 16 communicates with the port 9, so that when the passage 10 15 registers with the ports 7 and 8, during the intake stroke of the piston, the carbureted air is drawn into the cylinder, and when the passage 10 registers with the ports 6 and 9, during the exhaust stroke of the piston, the exhaust gases are forced out through the port 6, passage 10, ports 9 and 16 and exhaust pipe or manifold 20. By reversing the member 15, the carbureted air will flow into the cylinder from the port 6 and the 20 exhaust gases will force out through the port 7, thus reversing the operation of the engine.

The valve is lubricated, and for this purpose, the housing 2 has a longitudinal groove 23 extending along one wall of the bore 3, and has an inlet aperture 24 in said wall beyond one end of the groove 23. A lubricant supply tube or pipe 25 is connected to the housing 2 to communicate with the 30 aperture 24, and the housing 2 and cap 4 are provided with a passage or duct 26 extending from said wall of the housing beyond the other end of the groove 23 into the cap and having branches 27 and 28. The branch 35 40 45 50 55 60 65 70 75 80 85 90 95 100 105 110 115 120 125 130 27 opens into the auxiliary combustion chamber from the cap, and the branch 28 leads to the wall of the recess 13 and cylindrical surface of the boss 11 to lubricate the packing rings and accompanying parts. The valve 5 has longitudinal grooves 29 and 30 adjacent to its smaller and larger ends, and when the valve is in position for the flow of carbureted air into the cylinder during the intake stroke of the piston, the groove 29 registers with the aperture 24 and groove 23, and the groove 30 registers with one end of the groove 23 and the duct 26. The lubricant is supplied to the housing 2 by way of the tube or pipe 25 under pressure or by gravity, and during the intake stroke, the lubricant will flow by pressure or gravity assisted by the suction which extends into the housing 2. Thus, the lubricant will flow from the tube 25 through the aperture 24, groove 29, groove 23, groove 30 and duct 26, thereby supplying lubricant to the contacting surfaces of the housing and valve. The valve 5 cuts off the connection between the groove 23 and aperture 24 and duct 26 when the valve is moved away

from intake position, so that the flow of lubricant is intermittent, the grooves 23, 29 and 30 holding lubricant which is supplied to the walls of the housing and valve.

Fig. 5 shows a duct 24' communicating 70 with the lubricant chamber in the smaller end of the bore 3' into which lubricant flows from the tube 25', and the duct 24' is intermittently connected with the groove 23 by the groove 29. 75

Having thus described the invention, what is claimed as new is:

1. In an internal combustion engine, a valve housing including a cap and having a conical bore, a conical valve seated in said bore for controlling the flow of gas, the housing having an auxiliary combustion chamber therein between the larger end of the valve and cap, and the larger end of the valve and cap having an interfitting recess 80 and boss reducing the area of said combustion chamber, said combustion chamber surrounding the boss.

2. In an internal combustion engine, a housing having a conical bore with its larger 90 end open, a cap attached to the housing across the larger end of said bore and having a recess, and a conical valve seated within said bore for controlling the flow of gas and having a central boss at its larger end fitting 95 snugly in said recess to reduce the pressure against the larger end of the valve, there being an auxiliary combustion chamber between the larger end of the valve and cap adapted to communicate with a cylinder. 100

3. In an internal combustion engine, a housing, a valve working therein for controlling the intake and exhaust, said housing having a chamber to communicate with an engine cylinder, and means for supplying 105 lubricant to the housing, the housing and valve having coöperable lubricant conducting means communicating with said chamber and adapted to register when the valve is in intake position to suck the lubricant 110 from said means.

4. In an internal combustion engine, a housing having a conical bore and a combustion chamber at its larger end, a conical valve seated in said bore and rotatable to control the intake and exhaust, the housing having a duct communicating with said chamber, and means for conducting lubricant to the housing, the housing and valve having lubricant conducting grooves adapted 115 to register when the valve is in intake position for establishing communication between said means and duct. 120

5. In an internal combustion engine, a housing having a conical bore and a combustion chamber at the larger end of the bore, a conical valve rotatable and seated in said bore for controlling the intake and exhaust, the housing having a duct communicating with said chamber, a lubricant inlet, and a 125 130

lubricant groove between said duct and inlet, and the valve having grooves to establish communication between said groove and the lubricant inlet and duct when the valve is in intake position.

6. In an internal combustion engine, a housing having a conical bore, a cap secured to the housing across the larger end of said bore and having a recess, a conical valve 10 rotatable and seated within the bore for controlling the intake and exhaust and having a boss at its larger end working snugly in said recess, the housing having a lubricant groove, a lubricant inlet beyond one end of 15 the said groove and a lubricant duct beyond the other end of said groove and extending

into said cap and having branches, one extending to the cylindrical surface of the boss and the other communicating with the chamber between the larger end of the valve and 20 cap, the valve having grooves to establish communication between the aforesaid groove and inlet and duct when the valve is in inlet position.

In testimony that I claim the foregoing 25 as my own, I have hereto affixed my signature in the presence of two witnesses.

DANIEL H. FRANCIS.
